(57) **CLAIM**

The ornamental design for a polishing pad, as shown and described.

DESCRIPTION

FIG. 1 is a perspective view of a polishing pad embodying the inventive ornamental design;

FIG. 2 is a top view of the polishing pad of FIG. 1 illustrating a hook and loop fastener surface;

FIG. 3 is a bottom view of the polishing pad of FIG. 1 illustrating a microfiber material surface;

FIG. 4 is a side view of the polishing pad of FIG. 1; and,

FIG. 5 is a view of the opposite side of the polishing pad of FIG. 4.

In FIGS. 1 and 2, the stipple shading shown on the top surface of the polishing pad is provided to illustrate a hook and loop fastener surface material. In FIG. 3, the bottom surface is shown with a pattern fill of small irregular circles that are provided to represent a microfiber material surface.
